UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

DROP WEIGHT FOR PATTERN MECHANISM.

Application filed September 22, 1925. Serial No. 57,905.

To all whom it may concern:

Be it known that I, ELBRIDGE R. HOLMES, a citizen of the United States, residing at Worcester, in the county of Worcester and State of Massachusetts, have invented a new and useful Drop Weight for Pattern Mechanism, of which the following is a specification.

This invention relates to improvements in drop weights for the pattern mechanism of so-called Knowles looms and it is the general object of the invention to provide improved means whereby said weights may be moved to and held in inoperative position.

In the well-known Knowles head the vibrator connector has a slotted connection with the harness lever and in order to maintain operative contact therewith it is necessary to provide some yielding device which will hold the two members together but permit relative movement of the same as the vibrator lever rises and falls due to the motion of the gear to which it is connected. It is occasionally necessary to remove a defective vibrator and under such conditions it is desirable that the drop weights be moved to and held in inoperative position to facilitate removal. It is a more particular object of my invention to accomplish this result by providing each drop weight with a spring plunger having a reduced portion thereof to cooperate with a slotted frame which serves normally to guide the plunger but which is so arranged as to receive the reduced portion of the latter to hold the same together with the drop weights in raised position.

It is a more specific object of my invention to connect the spring for the plunger to the drop weight to cause the latter to move with the plunger.

With these and other objects in view which will appear as the description proceeds, my invention resides in the combination and arrangement of parts hereinafter described and set forth in the claims.

In the accompanying drawings wherein a convenient embodiment of my invention is set forth,

Fig. 1 is a vertical longitudinal section through a Knowles head motion showing my invention applied thereto,

Fig. 2 is an enlarged horizontal section on line 2—2 of Fig. 1,

Fig. 3 is a section on line 3—3 of Fig. 2, 55

Fig. 4 is a section on line 4—4 of Fig. 2, and

Fig. 5 is an enlarged fragmentary elevation of the lower end of the plunger and spring therefor showing the way in which these parts are connected to the drop weight. 60

Referring to the drawings it will be seen that I have provided a loom 10 having a head frame 11 on which are mounted upper and lower oppositely but constantly rotat- 65

ing mutilated gear cylinders 12 and 13, respectively. Disposed between said cylinders is the usual gang of vibrator gears 14 one of which is shown in Fig. 1, and each of 70

said gears is mounted on a vibrator lever 15. A pattern chain 16 controls the vertical position of the vibrator levers and the latter move under control of the chain about a heel pin 17. Vibrator connector 18 has one 75

end attached as at 19 to the vibrator gear and the other end slotted as at 20 to engage a gudgeon 21 carried by each harness lever 22. Said harness levers are pivoted on the cross rod 23 and are operatively connected 80

to the harness of the loom. A plurality of drop weights 24, one for each connector 18, are pivoted on a rod 25 extending between the arches of the loom. The matter 85

thus far described is of well known construction and in the operation thereof the vibrator levers 15 will be raised or lowered to bring the vibrator gears into operative contact with one or the other of the oppositely rotating mutilated gear cylinders to the end that the connectors 18 and the harness levers connected thereto may be recipro- 90

cated under control of the pattern chain to determine the weave. 95

My improvements relate more particularly to the plunger rod associated with each drop weight 24 and the manner in which the same is connected to the drop weight and also to the manner in which it may be moved to in- 100

operative position. In carrying out my invention I provide a plunger rod 30 for each drop weight and the lower end of each rod is provided with an enlarged rounded head 31 to be received by a depression in cup 32

formed on each drop weight 24. The cup has at one side thereof an upstanding lug 33 through which extends the lower end of compression spring 34 which surrounds the plunger 30. The upper end of each spring 105

34 presses against a frame 35 held in fixed position with respect to the loom and having therein a plurality of openings each provided with a circular portion 36 and a slot 5 37 communicating therewith. Each rod has a slabbed or reduced portion 38 formed intermediate the ends thereof proportioned to be received by the slots 37. The body of the rod is of such diameter as will pass 10 freely through the circular opening 36 but will not pass through the slots 37.

Under normal conditions the springs 34 will press the drop weights 24 against the vibrator connectors 18 but when it is desired 15 to remove the vibrator the corresponding drop weight will be moved into the associated slot 37. That part of the rod which lies above the slabbed or reduced portion 38 will then engage the top of the frame 35 20 and hold the drop weight in raised position. Because of the fact that the lower end of the spring 34 passes through the lug 33 the drop weight will be held in raised position. I find it convenient to so proportion the up- 25 standing tail 39 of the drop weight as to engage the plunger rod 30 and move the same to the dotted line position shown in Fig. 1 with the reduced portion 38 lying in the slot 37. When the vibrator lever is 30 being removed the connector 18 will be raised to the dotted line position shown in Fig. 1 so that it will be free from the gudgeon 21 and be movable endwise out of the head. After a new lever has been inserted 35 in the head the corresponding plunger will be moved away from the slot 37 and will again be operative to hold the connector 18 in proper position.

From the foregoing it will be seen that I 40 have provided a very simple device for raising and holding the drop weights of the well-known Knowles head in inoperative position without requiring constant attention on the part of the operator. It will 45 further be noted that the connection between the spring and the drop weight is such that the raising of the plunger 30 also raises the drop weight 24 and that each tail 39 is proportioned to move the plunger 50 associated therewith to inoperative position. Furthermore each plunger is freely rotatable with respect to its drop weight to permit registry of the slabbed portion thereof with the slot 37.

Having thus described my invention it 55 will be apparent that changes and modifications may be made therein by those skilled in the art without departing from the spirit and scope of the invention, and I do not 60 wish to be limited to the details herein disclosed but what I claim is:

1. In a loom pattern mechanism having a harness lever and an operating connector removably attached thereto, a drop weight 65 operating normally to hold the connector

and lever in operative relation, yielding means to hold the weight against the connector, and a support to hold said yielding means temporarily in position to relieve the pressure between said drop weight and the connector. 70

2. In a loom pattern mechanism having a harness lever and an operating connector removably attached thereto, a drop weight 75 operating normally to hold the connector and lever in operative relation, yielding means to hold the weight against the connector, a support to hold said yielding means temporarily in position to relieve the pressure between said drop weight and the connector, and connections between the weight and yielding means to cause said weight to move away from the connector when said yielding means is moved to relieve pressure on the connector. 80

3. In a loom pattern mechanism having a harness lever and an operating connector removably attached thereto, a drop weight 85 operating normally to hold the connector and lever in operative relation, a plunger 90 for the drop weight, a head formed on the plunger and received by a depression in the drop weight, a spring surrounding the plunger and extending through a portion of the drop weight, and means to hold the plunger in position to relieve pressure on the connector, the portion of the spring which extends through the drop weight holding the latter away from the connectors. 95

4. In a loom pattern mechanism having a harness lever and an operating connector removably attached thereto, a drop weight 100 operating normally to hold the connector and lever in operative relation, a plunger 105 for the drop weight having a portion of reduced cross-section, a support having a slot located above the normal position of the reduced part of the plunger and positioned to receive said reduced part of the plunger when the latter is raised, and yielding means surrounding the plunger and engaging a portion thereof to hold said plunger against the drop weight, said means being operatively connected to the drop weight to cause said weight to move with the plunger. 110

5. In a loom pattern mechanism having a harness lever and an operating connector removably attached thereto, a drop weight 115 operating normally to hold the connector and lever in operative relation, a plunger 120 for the drop weight having a portion of reduced cross-section, a support having a slot located above the normal position of the reduced part of the plunger and positioned to receive said reduced part of the plunger when the latter is raised, and yielding means surrounding the plunger and engaging a portion thereof to hold said plunger against the drop weight, said means being operatively connected to the drop weight to cause said weight to move with the plunger. 125

drop weight to cause said weight to move with the plunger, said plunger being freely rotatable with respect to the drop weight, thereby permitting movement of said plunger to cause the reduced part thereof to register with the slot of the support. 5

6. In a loom pattern mechanism having a harness lever and an operating connector removably attached thereto, a drop weight 10 operating normally to hold the connector and lever in operative relation, a spring plunger connected to the drop weight and holding the same against the connector, said plunger having a portion of reduced cross-

section, a giveway support for the plunger having an opening therein to receive the plunger and a lesser opening connected to the first opening to receive the portion of the plunger having a reduced cross-section, and a tail projecting from the drop weight 20 and proportioned to engage the plunger when the same is raised and move the reduced portion of the plunger into the lesser opening of the support.

In testimony whereof I have hereunto 25 affixed my signature.

ELBRIDGE R. HOLMES.
